(57) **CLAIM**

The ornamental design for a daisy chair, as shown and described.

DESCRIPTION

FIG. 1 is a top plan view of a daisy chair showing my new design;

FIG. 2 is a bottom plan view thereof;

FIG. 3 is a back elevational view thereof;

FIG. 4 is a front elevational view thereof;

FIG. 5 is a left elevational view thereof;

FIG. 6 is a right elevational view thereof;

FIG. 7 is a front perspective view thereof;

FIG. 8 is a back-perspective view thereof;

FIG. 9 is an alternate front perspective view thereof;

FIG. 10 is an alternate back perspective view thereof;

FIG. 11 is a bottom perspective view thereof;

FIG. 12 is an alternate bottom perspective view thereof;

FIG. 13 is a second alternate bottom perspective view thereof; and,

FIG. 14 is a third alternate bottom perspective view thereof. The broken lines shown in the figures are for the purpose of illustrating environment and form no part of the claimed design.
